UNITED STATES PATENT OFFICE.

WILLIAM R. FOX, OF GRAND RAPIDS, MICHIGAN, ASSIGNOR TO THE FOX MACHINE COMPANY, OF SAME PLACE.

SASH-CORD GUIDE.

SPECIFICATION forming part of Letters Patent No. 669,578, dated March 12, 1901.

Application filed June 20, 1898. Serial No. 683,957. (No model.)

To all whom it may concern:

Be it known that I, WILLIAM R. FOX, a citizen of the United States, residing at Grand Rapids, Kent county, Michigan, have invented 5 certain new and useful Improvements in Sash-Cord Guides, of which the following is a specification.

My invention relates to improvements in sash-cord pulleys and shells, commonly called 10 "sash-cord guides," constructed of sheet metal.

The object of the invention is to provide a construction which may be produced at an extremely low cost by stamping from sheet metal 15 and in which all necessity of riveting the parts together may be dispensed with.

The invention is illustrated in the accompanying drawings, in which—

Figure 1 is a side elevation. Fig. 2 is an 20 end view, and Fig. 3 is a detail sectional view. Fig. 4 is an end elevation, and Fig. 5 a detail view.

The shell or casing shown in Fig. 1 consists 25 of two portions or halves B B, which are precisely alike in shape and are struck from a suitable sheet-metal blank. Each half or section is preferably provided approximately centrally thereof with a circular depression or concavity, as shown at b, having an angular 30 hole to receive the end of the axle C, and is also provided with parallel corrugations b', extending from the rear to near the face of the shell for the purpose of strengthening and bracing the shell and also filling the auger- 35 holes where the sides of the mortise are not cut plain. The sides are curved inwardly at top and bottom until in contact with each other, at which point they are provided with parallel flanges B', forming a broader bearing and preventing the slipping of the edges 40 one from the other. These abutting flanges are cut or otherwise formed into saw-teeth, serving to cut their way as the shell is driven into the wood, thereby preventing the wood 45 from splitting.

The pulley A turns on a shouldered axle or rivet, which has its reduced ends passed through openings in the side sections and headed over to hold it securely in place.

50 In order to prevent any relative displacement of the side sections while they are being handled, I connect them at top and bottom

by turning over one or more of the teeth e of one section into a space formed by omitting the corresponding tooth of the opposing section. I prefer to bend over several of the teeth in this manner, as shown more clearly in Fig. 3, and the fastening is rendered more secure by turning the teeth alternately first from one section and then from the other. 55 The front edges of the sections are preferably turned over to form flanges to provide a bearing against the face of the wood into which the shell is driven, and these flanges extend entirely around the face of the shell and abut 60 against each other at D. The abutting edges are slightly recessed, as shown at D, so that an opening is formed at top and bottom of the shell for the insertion of a nail to hold the shell in the wood. Just in rear of each 65 flange is an interior vertical rib d, formed by the metal being struck inwardly into close proximity to the pulley, whereby the latter is guided and the sash-cord prevented from jumping from the pulley and getting between 70 it and the walls of the shell. The channel or depression also adds strength and rigidity to the shell. 75

Having thus described my invention, what I claim is—

1. A shell of a sash-cord guide, consisting 80 of duplicate sides having on the inwardly-turned ends, parallel flanges provided with serrated edges, and with one or more of the teeth of said edges turned to interlock, substantially as described.

2. A shell for a sash-cord guide comprising 85 duplicate sides having inwardly-turned abutting upper and lower ends, and outwardly-turned front edges forming a face-flange, said sides having plain-bottomed channels or depressions adjoining the face-flanges and forming interior ribs, parallel corrugations extending from the rear toward the front and terminating in said depressions and means 90 for holding said sections together, substantially as described.

In testimony whereof I affix my signature in presence of two witnesses.

WILLIAM R. FOX.
